(No Model.)

W. G. PARSONS.
BICYCLE RACK.

No. 595,967.

Patented Dec. 21, 1897.

UNITED STATES PATENT OFFICE.

WALTER G. PARSONS, OF ENGLEWOOD, NEW JERSEY.

BICYCLE-RACK.

SPECIFICATION forming part of Letters Patent No. 595,967, dated December 21, 1897.

Application filed April 13, 1897. Serial No. 632,016. (No model.)

To all whom it may concern:

Be it known that I, WALTER G. PARSONS, of Englewood, in the county of Bergen and State of New Jersey, have invented a new 5 and Improved Bicycle-Rack, of which the following is a full, clear, and exact description.

My invention relates to an improved form of rack for stowing bicycles, designed especially for use in connection with baggage-cars, but applicable to use in any situation 10 where space is limited and it is desired to stow a number of bicycles.

Reference is to be had to the accompanying drawings, forming a part of this specification, 15 in which similar characters of reference indicate corresponding parts in all the figures.

Figure 1 is a perspective view of my device as applied to a baggage-car. Fig. 2 is a detail section of the eye at the end of the longitudinal bars. Figs. 3, 4, and 5 are details 20 of modified forms of hooks.

In transporting bicycles in baggage-cars the question of storage of the same has given a great deal of trouble. My device is designed 25 to stow the bicycles in such a manner that they will occupy as little space as possible in that portion in the upper part of the car where it is the least available for stowing heavy matter, such as trunks; also, to make any one 30 of the bicycles readily accessible without disturbing the others.

In carrying out my invention I provide lateral bars D, which are supported at each end upon some fixed object. In placing the same 35 within baggage-cars this support is provided by fastening U-shaped brackets or sockets C upon the side of the car just beneath the roof. These are placed a distance apart considerably less than the longest dimension of 40 a bicycle. This would approximately be about three feet.

The bar D would extend entirely across the baggage-car. These bars would also be made in pairs. Upon these bars are placed longitudinal bars E. These bars are provided with 45 eyes G at each end, having holes adapted to fit over the bars D, so that the bars E may be slid thereon to any point desired. These eyes consist of a cylindrical portion adapted 50 to embrace the bars D and a flange or socket G', extending therefrom to one side and adapted to receive the end of the bar E. The bar

E is fastened securely thereto by a bolt g or a rivet, if the separation of these two parts is not desired. A number of these longitudinal bars are placed upon each pair of lateral bars. Upon each of these longitudinal bars are placed at least two hooks F. The bars themselves are made of a polygonal section or one which will prevent the hooks from 55 turning on the bars. In the drawings the bars E are shown as made flat.

The hook F is provided with a hole fitting snugly upon the bar E, so that the hook may be readily moved thereon. The hook has a 60 horizontally-extending arm f, which acts as a hook upon which the bicycle-frame may be placed. For convenience in adjusting the height of the hook and also the angle at which it projects I have shown a hook H, which 70 consists of a threaded shank h and a horizontal arm extending from the lower end thereof and forming the hook proper. The shank h of this hook is threaded into a hole 75 passing through the hook F. The hook H can thus be adjusted considerably in height and also in its direction of projection.

In using my device the upper horizontal bar of the bicycle-frame or any other convenient portions—as, for instance, the handle-bar and saddle—may be placed over the hooks f and H, thus supporting the bicycle in the upper portion of the car, leaving the lower portion of the car free for baggage of any kind.

In many cases the hooks f will be found 85 more convenient, as they will support the wheel at a higher elevation than will the hooks H. In many cases, as in a drop-frame machine, it will be necessary to have a hook projecting in a different direction from the hook 90 f, in which case the hook H is available. This also permits of considerable adjustment and makes it possible to support the bicycle from a point considerably below its upper part. It also makes it possible to suspend two wheels 95 from one bar, if desired.

The hook shown in Fig. 3 is a modification of the hook H of Fig. 1. This hook consists of the threaded shank h and a head at its lower end, which has two horizontal hooks H' 100 slightly separated from each other. This is a more convenient form for engagement with the handle-bar or saddle of a bicycle than that shown in Fig. 1.

Fig. 4 shows another form of hook and consists of the eye F^2 , adapted to embrace the bar E, and the downwardly-projecting and upwardly-curved hooks f' . In using this form 5 of hook the curved portions f' should project laterally and longitudinally also—that is, in a direction diagonal to the direction of the bar E. This makes it possible to place the handle-bar of a machine over the hooks or to 10 place the upper bar of the frame over the hooks.

Fig. 5 shows another form of hook, consisting of a Z-shaped bar F' , having one end corresponding to the hook f . (Shown in Fig. 15 1.) The bar F' is also provided with an eye to which is fastened a small chain f^3 and a double hook f^2 .

In using my device the bar which is next to the wall will first be filled by hanging a wheel 20 thereon, the next wheel will be hung upon the next bar outside this, and so on until the space is completely filled. The bars which are not in use may be pushed over to one side of the car or to the space in the center of the 25 car and the bars next to the wall be gradually filled, leaving, finally, an open space only in the center of the car. In case it is desired to remove one of the bicycles which is near the side of the car those bars which are outside 30 of the one carrying such bicycle will be slid to the opposite side of the car or to the center until the desired bicycle is uncovered, and it may then be easily removed and the other bicycles moved back to their former positions.

35 In placing bicycles upon the bars E it is desirable that each alternate machine be reversed in position—that is, that the front wheel of one bicycle be placed in the direction of the rear wheel of the other bicycle. This 40 prevents the front wheel from swinging upon its pivot.

This device is readily taken down and stored when it is not needed.

The bars E may be moved from the bars D 45 by sliding them off from one end thereof. The bars D are readily taken down by lifting them out of the brackets C. The whole device is placed at such an elevation in the car that it will not interfere with the baggage- 50 men passing thereunder. When not filled with bicycles, the device will therefore be found to be out of the way and will create no inconvenience when not in use. It also leaves the entire floor-space of the car available for 55 trunks or other heavy baggage and securely supports the bicycles where they will not be damaged by coming in contact with such baggage. It also renders the bicycles readily accessible and prevents their becoming entangled 60 with one another and avoids the damage liable to result therefrom.

This device is applicable as well to hotels and other places where bicycles are liable to be stored and where space is valuable. It

possesses the same merits for such locations 65 as when used in baggage-cars.

Having thus fully described my invention, I claim as new and desire to secure by Letters Patent—

1. A bicycle-rack, comprising lateral bars 70 arranged in pairs and supports therefor at each end, longitudinal bars having eyes in each end, fitting and sliding upon the lateral bars, and hooks supported to slide without turning upon the longitudinal bars, substan- 75 tially as described.

2. A bicycle-rack, comprising lateral bars arranged in pairs and supports therefor at each end, longitudinal bars having eyes at each end fitting and sliding upon the lateral 80 bars, blocks fitted to slide without turning upon the longitudinal bars and having a vertical threaded hole, and hooks having threaded shanks fitting said holes, substantially as described. 85

3. A bicycle-rack, comprising lateral bars arranged in pairs and supports therefor at each end, longitudinal bars having eyes at each end fitting and sliding upon the lateral 90 bars, blocks fitted to slide without turning upon the longitudinal bars, having each a horizontally-extending hook fixed thereto, and also having a vertical threaded hole, and hooks having threaded shanks fitting said holes, substantially as described. 95

4. A bicycle-rack, comprising lateral bars, U-shaped blocks supporting the ends thereof, longitudinal bars of a polygonal section, eyes fitting and sliding upon the lateral bars, having a socket in one side to receive the end 100 of the longitudinal bars, and hooks upon the longitudinal bars fitted to slide thereon without rotation, substantially as described.

5. A bicycle-rack, comprising two lateral bars, supports for each end thereof, longitudinal bars of a non-circular section, eyes fitting and sliding on the lateral bars, having a socket in one side to receive the ends of the longitudinal bar, hooks upon the longitudinal 105 bars fitted to slide thereon without rotation and having vertical threaded holes therein, and hooks having threaded shanks fitting therein, substantially as described. 110

6. A bicycle-rack, comprising two lateral bars, supports for each end thereof, longitudinal 115 bars of a non-circular section, eyes fitting and sliding on the lateral bars, having a socket in one side to receive the ends of the longitudinal bar, hooks upon the longitudinal 120 bar fitted to slide thereon without rotation and hooks attached thereto adjustable in height and in angular position, substantially as described.

WALTER G. PARSONS.
